UNITED STATES PATENT OFFICE.

CONRAD C. BROSCH, OF MORGAN, MINNESOTA.

ADJUSTABLE TONGUE ATTACHMENT FOR VEHICLE HOUNDS.

Application filed February 21, 1927. Serial No. 169,950.

The invention relates to a wagon hound or appliance and more particularly to the class of wagon tongue draft hounds.

The primary object of the invention is the provision of a hound of this character, wherein the construction thereof enables the quick and easy adjustment of the same so that it can be attached to wagons and trucks and all vehicles adaptable for the use of a tongue-hound, the hound and the adjustments for the same being of novel construction.

Another object of the invention is the provision of a hound of this character, wherein the tongue can be easily and conveniently adjusted according to the line of draft of the vehicle with which the same is to be attached, and when so adjusted will be held rigid and firm against undue vibration at the point of juncture of the same with the hound.

A further object of the invention is the provision of a hound of this character, wherein the same can be easily adjusted to any wagon or vehicle to which a tongue is to be attached and also to permit the continued use of the tongue, irrespective of the fact that the same may have become bent or crooked without in any manner affecting the draft of the wagon or other vehicle, so that the same will travel true.

A still further object of the invention is the provision of a tongue hound of this character, which is extremely simple in construction, thoroughly reliable and efficient in its purpose, strong, durable, readily and easily adjusted, neat in appearance, and inexpensive to manufacture and install.

With these and other objects in view, the invention consists in the features of construction, combination and arrangement of parts, as will be hereinafter more fully described, illustrated in the accompanying drawing showing the preferred embodiment of the invention, and pointed out in the claims hereunto appended.

In the accompanying drawing:

Figure 1 is a fragmentary top plan view, partly broken away showing the adaptation with the wagon hound and draft tongue of an adjustable tongue attachment in accordance with this invention.

Figure 2 is a fragmentary side elevation taken approximately on the line 2—2 of Figure 1, looking in the direction of the arrow.

Figure 3 is a detailed sectional view taken

on the line 3—3 of Figure 1 looking in the direction of the arrow.

Figure 4 is a fragmentary sectional view on the line 4—4 of Figure 1.

Similar reference characters indicate corresponding parts throughout the several views in the drawing.

Referring to the drawing in detail A designates generally a portion of the forwardly convergent side members of the wagon front hound, these being of the conventional form and between which is adapted to be disposed the draft tongue B of the ordinary well known type. Arranged between the side members A and tongue B is an adjustable connecting means therefor, and which includes a pair of opposed, forwardly converging channel members 5 and a pair of forwardly converging angle shaped brackets or straps 6. The members 5 are positioned against the inner face of the side members A, project forwardly from the forward ends of said side members A and have their forward ends, inset as at 7, for the reception of the rear ends of the brackets or straps 6. Extending through the side members A, channel shaped members 5 and tongue B, transversely and intermediate the ends thereof is a tie-bolt 8 carrying nuts 9 and 10 which are adapted to be seated in the outer side faces of the side members A whereby the members A and 5 and tongue B are connected together.

Extending loosely through the inset forward ends 7 of the members 5, the rear ends of the brackets 6 and the tongue B is a threaded rod carrying a pair of jamb nuts 15 and two pair of jamb nuts 16. The jamb nuts 15 are positioned against the side edges of the tongue B and the two pair of jamb nuts 16 are positioned against the inner faces, at the rear ends of the straps 6, and against the outer faces of the inset ends 7 of the members 5. The jamb nuts 16 are held against adjustment through the medium of cotter pins 17 removably fitted in the inset ends 7 of the members 5 and abutting the wrench engageable surfaces of such nuts. By the arrangement of the jamb nuts 15 and threaded bar 14, with respect to the tongue B, brackets 6, and members 5, rod 14 can be adjusted by altering the position of the nuts 15 to assist in truing the tongue B relative to the wagon hound.

Carried by the tongue B at its rear end, on opposite sides thereof, are opposed resilient

loops 18 having their inner stretches fixedly secured to the tongue B, by the holdfast devices 19.

Connected with the channel shaped members 5, and extending loosely through the centers of the loops 18 and into a passage 21 formed in the tongue B, are oppositely disposed adjusting rods 20. Adjustably engaging with the rods 20 and working against the outer stretches of the loops 18 are pairs of jamb nuts 22 which adjustably connect the loops and said rods 20 together, these nuts being held in adjusted position through the medium of cotter pins 23 fastened in the outer stretches of the loops 18 as is clearly shown in Figure 1 of the drawing.

The rods 20 also carry nuts 24 which work against the inner stretches of the loops 18 to limit the inward movement of the rods to prevent the same from advancing too far inwardly of the passage 21 in the tongue B.

It will be apparent that by adjustment of the nuts 15, 16, and 22, the tongue B can be adjusted to have the same true with regard to the line of draft of a vehicle and held rigid in the tongue hound.

The outer ends of the rods 20 are formed with pivot eyes 25, which are received in the channel members 5, and have engaged therein pivots 26, connecting the rods 20 to said members 5, as will be apparent.

It is of course to be understood that changes, variations, or modifications may be made in the structure as come properly within the scope of the appended claims, without departing from the spirit of the invention or sacrificing any of its advantages.

From the foregoing it is thought that the construction and manner of use of the hound will be clearly understood and therefore a more extended explanation has been omitted.

What is claimed is:—

1. An adjustable tongue attachment for a wagon hound, comprising a pair of forwardly converging side elements for positioning against and to project forwardly from the side members of the hound, a pair of angle shaped brackets for connection to the tongue and having the rear ends thereof abutting against the forward ends of said elements, and adjusting coupling connection between said ends and the tongue, coupling means between said elements, tongue and side members, a pair of resilient loops, means for securing the inner stretches of said loops to the sides of the tongue, a pair of oppositely disposed, threaded adjusting rods pivotally connected at their outer ends to said elements, loosely extending through said loops and into the tongue, and jamb nuts carried by said rods and adjustably engaging with the outer and inner stretches of the loops.

2. An adjustable tongue attachment for a

wagon hound, comprising a pair of forwardly converging side elements for positioning against and to project forwardly from the side members of the hound, a pair of angle shaped brackets for connection to the tongue and having the rear ends thereof abutting against the forward ends of said elements, and adjusting coupling connection between said ends and the tongue, coupling means between said elements, tongue and side members, a pair of resilient loops, means for securing the inner stretches of said loops to the sides of the tongue, a pair of oppositely disposed, threaded adjusting rods pivotally connected at their outer ends to said elements, loosely extending through said loops and into the tongue, and jamb nuts carried by said rods and adjustably engaging with the outer and inner stretches of the loops, said elements being of channel shaped cross section opening towards the tongue, and said brackets having their rear ends seated in the forward ends of said elements.

3. An adjustable tongue attachment for a wagon hound, comprising a pair of forwardly converging side elements for positioning against and to project forwardly from the side members of the hound, a pair of angle shaped brackets for connection to the tongue and having the rear ends thereof abutting against the forward ends of said elements, an adjusting coupling connection between said ends and the tongue, coupling means between said elements, tongue and side members, a pair of resilient loops, means for securing the inner stretches of said loops to the sides of the tongue, a pair of oppositely disposed, threaded adjusting rods pivotally connected at their outer ends to said elements, loosely extending through said loops and into the tongue, jamb nuts carried by said rods and adjustably engaging with the outer and inner stretches of the loops, and means carried by the outer stretches of the loops and engaging the jamb nuts which abut against such stretches for retaining such jamb nuts in set position.

4. An adjustable tongue attachment for a wagon hound, comprising a pair of forwardly converging side elements for positioning against and to project forwardly from the side members of the hound, a pair of angle shaped brackets for connection to the tongue and having the rear ends thereof abutting against the forward ends of said elements, an adjusting coupling connection between said ends and the tongue, coupling means between said elements, tongue and side members, a pair of resilient loops, means for securing the inner stretches of said loops to the sides of the tongue, a pair of oppositely disposed, threaded adjusting rods pivotally connected at their outer ends to said elements, loosely extending through said loops and into the tongue, jamb nuts carried by

said rods and adjustably engaging with the outer and inner stretches of the loops, said elements being of channel shaped cross section and opening towards the tongue, said bracket having their rear ends seated in the forward ends of said elements, and means carried by the outer stretches of the loops

and engaging the jamb nuts abutting against such stretches to retain such jamb nuts in adjusted position.

In testimony whereof, I affix my signature hereto.

CONRAD C. BROSCH.
